LIFTING JACK

Arthur Clifford Howard, Upminster, England

Application February 20, 1948, Serial No. 9,726
In Great Britain March 14, 1944Section 1, Public Law 690, August 8, 1946
Patent expires March 14, 1964

2 Claims. (Cl. 74—169)

1

This invention relates to lifting jacks of the kind having a rack provided with ratchet teeth that is slidably supported in a pedestal, and two pawls by which the rack is raised, retained, and lowered; the rack being provided with a lifting head, and one or both pawls being respectively pivoted to a hollow operating lever according as to whether the jack is single- or double-acting.

With single-acting jacks of the kind set forth, it has been the practice to pivot a lifting pawl by trunnions in bearings formed in the sides of the hollow operating lever in a position between the fulcrum of the latter and the rack, and to pivot a detent pawl to the pedestal in a position above the lifting pawl. In this way, when the operating lever has been depressed, the lifting pawl raised the rack a distance slightly greater than one tooth, and the detent pawl engaged the tooth next below the one it previously engaged. Upon raising the operating lever, the rack was permitted to rest upon the detent pawl, and the lifting pawl was lowered into engagement with the tooth next below the one it previously engaged in readiness for lifting the rack another step. Both of the pawls were so poised or spring-loaded that they were urged against the rack, and suitable means for lowering the rack were provided whereby the poise or spring-loading of the two pawls could be modified so that upon depressing the operating lever, the lifting pawl raised the rack just sufficiently to free the detent pawl and permit it to be retracted from the rack, and upon raising the operating lever the rack was lowered under the control of the lifting pawl until the detent pawl moved into engagement with the next higher tooth on the rack.

With double-acting jacks of the kind set forth, the construction was similar to that above described but with the principal difference that the detent pawl was supported by trunnions in bearings formed in the sides of the hollow operating lever, but on the opposite side of the fulcrum to the bearings for the lifting pawl, and itself acted as a second lifting pawl. In this way, the rack was raised one tooth for each upward and each downward movement of the operating lever. Similarly, when the poise or spring-loading of the two pawls had been modified as referred to above, the rack was lowered by one tooth for each upward and each downward movement of the operating lever.

A cardinal limiting factor of the mechanical advantage obtainable with jacks of the kind set forth is the amount of metal that must be allowed to remain between the bearings for the ful-

crum pin of the operating lever and for the trunnions of the pawl or pawls in order that the operating lever was not weakened.

Accordingly, the present invention has for its object a method of supporting the operating lever and lifting pawl of a single-acting jack of the kind set forth, and the operating lever and lifting and detent pawls of a double-acting jack of the kind set forth, so that the axes of said pawl or pawls can be set nearer to the operating lever fulcrum than has hitherto been possible without undesirably weakening the operating lever.

According to the invention, a hollow operating lever, for a single-acting jack of the kind set forth, has a pair of trunnions which serve for fulcrumming the lever in the jack, and has a bearing barrel arranged, with its axis parallel to, but off-set from, the axis of the trunnions, to bridge an opening in the lever in the region of the trunnions, and to provide a convex bearing surface to coact with a corresponding concavity in the foot of the lifting pawl, which latter is held in this position so as to be rockable circumferentially of the barrel.

Also according to the invention, a hollow operating lever, for a double-acting jack of the kind set forth, has a pair of trunnions which serve for fulcrumming the lever in the jack, and has a pair of bearing barrels arranged with their axes parallel to, but off-set on opposite sides from, the axis of the trunnions, to bridge an opening in the lever in the region of the trunnions, each of the barrels providing a convex bearing surface to coact with a corresponding concavity in the feet of the lifting and detent pawls, respectively, which pawls are held in these positions so as to be rockable circumferentially of the associated barrels.

The, or each, pawl can be held in position on its bearing barrel by a metal strap which is secured to the former and passes either completely or partially around the barrel. In the case of a double-acting jack, these straps can be of the latter type and be passed over the remote sides of the two barrels so as to permit of there being a minimum of space between the latter.

The operating lever, trunnions, and bearing barrels may be cast in one piece, in which event the lower portions of the trunnions and bearing barrels at their adjacent ends may merge into each other, so as to enhance the strength of the casting, and a space is left between the bottoms of the bearing barrels and the lower wall 55 of the hollow operating lever so as to accommo-

date the aforesaid straps. Alternatively, the structure may be welded together or otherwise fabricated.

The aforementioned straps may be J-shaped so that they can be secured to their respective pawls, as by riveting, and extend sufficiently round their respective bearing barrels to retain the pawls in position. Alternatively, particularly in the case of a single-acting jack, the straps may be U-shaped and have both ends attached to the pawl. The straps may, in some instances, be recessed into their pawls and bearing barrels.

A major advantage accruing from the present invention is the fact that the diameters of the trunnions and bearing barrels can be made of adequate size without reference to the distance between their respective axes, also, that as the bearing barrels can be set above the level of the trunnions, the full width of the former can be utilised for the bearing surface for the pawls.

In the accompanying drawings,

Fig. 1 is a side elevation, in part section, of a double-acting jack, of known type, embodying the present invention, and showing a tommy bar in position,

Fig. 2 is a plan view, in part section, of the operating lever showing the arrangement of the lever trunnions and the bearing barrels,

Fig. 3 is a longitudinal section indicated by the arrows 3—3 in Fig. 2,

Fig. 4 is an end view from the left of Fig. 2,

Fig. 5 is a detail view of one of the pawls,

Fig. 6 is a view corresponding to Fig. 2 but showing one of the pawls in position, and

Figures 7 and 8 are views corresponding respectively with Figures 1 and 3 but illustrating a single-acting jack according to the invention.

Referring now to the drawings, the jack comprises a pedestal 1 having a foot 2 and a handle 3 by which the jack can be moved from place to place. The pedestal contains a rack 4 having ratchet teeth and is surmounted by a lifting head 5. A hollow operating lever 6, the construction of which will be described later, is pivoted in the pedestal and carries a lifting pawl 7 and a detent pawl 8. The two pawls are connected by a spring-loading device, indicated generally at 9, incorporating a bell-crank lever 10 and a connecting rod 11 by which the spring-loading on the pawls is modified so as either to cause the rack to be raised step-by-step, or lowered in the same way, for each up and down movement of the operating lever, and according to the position of the bell-crank. This raising and lowering mechanism is of known kind and, as stated above, the improvements effected by the present invention reside in the formation and disposition of the pivots for the operating lever and the two pawls.

The operating lever 6 has two integral trunnion pins 12 projecting outwardly from its side walls and adapted to be received in bearings in the sides of a slot in the pedestal. The inner end of the lever 6 is open at the top, and the said side walls are bridged by two bearing barrels 13 and 14, also formed integrally therewith. The lower portions of the adjacent sides of the barrels, at their ends, are preferably faired into the side walls of the operating lever, as indicated at 15, for the purpose of strengthening the structure, and a space is left between the bottoms of the barrels and the lower wall of the lever, as indicated at 16, for the purpose hereinafter described.

The foot of each pawl is provided with a con-

cave cylindrical surface 17 adapted to form the bearing surface on the respective barrels 13 and 14, and the two pawls are held on their barrels by substantially J-shaped straps 18 riveted to them and extending under the barrels. These straps are secured to the remote sides of the pawls, preferably within slots in the latter, and, together with the surfaces 17, embrace more than half of the circumference of the barrels, the straps passing through the spaces 16 between the bottoms of the barrels and the lower wall of the operating lever.

It will be seen that the pawls can be mounted much closer together and to the operating lever fulcrum than if they were themselves pivoted upon pins, as hitherto, with a resultant increase in the mechanical advantage obtained. Also, owing to the greatly increased bearing area, and the robustness of the bearing barrels, as compared with the pins as hitherto used, a greater load, commensurate with the enhanced mechanical advantage, can be sustained without danger of damaging the jack. Furthermore, the trunnions 12 can be made more robust than the pivot pin hitherto used for supporting the operating lever, and as these trunnion pins are on the opposite sides of the side walls of the operating lever to the bearing barrels for the pawls, said pins and barrels can be made to overlap.

The straps 18 serve merely to locate the pawls and do not take any further load; they can, therefore, be made narrow, and the spaces between and beneath the barrels, need be only of sufficient size to accommodate them, thus avoiding unduly increasing the size of the operating lever to secure adequate strength.

The single-acting jack illustrated by Figures 7 and 8 has its parts indicated by like reference numerals, and it will be seen that it only differs from the double-acting jack in that the barrel 14 is omitted and the pawl 8a is pivoted to the jack body at 14a.

In both forms of the invention spaced side walls 20 at the inner end of the handle 6 define a space which is open upwardly and outwardly and closed only at the sides by the walls 20 and at the lower part by a bottom wall 21 which may have at its free end an upstanding rib 22 which may be in the same general vertical plane with the trunnions 12 and in the case of Figure 3 projects up toward the space between the two bearing barrels 13 and 14, and generally acts to strengthen the structure.

It will be noted that the bearing barrel or barrels bridge the space between the side walls 20 and are spaced above the bottom wall 21 and its rib 22, while the trunnions 12 are completely outside the space confined between the side walls 20 and in fact project laterally in opposite directions from the outside surfaces of the side walls 20.

Whilst the invention has been described with reference to one form of lifting jack, it will be understood that it is equally applicable to the support of operating levers and the pawls mounted thereon for use with other types of jack.

What I claim as my invention and desire to secure by Letters Patent of the United States is:

1. For use with a jack having a pedestal and a rack bar slidable in the pedestal, an improved operating handle and pawl construction comprising a handle member having spaced walls at an end portion thereof with the space between the walls opening upwardly and out-

wardly, trunnions integral with said walls projecting laterally therefrom and adapted to be journaled in the pedestal, a bearing barrel integral with said side walls and disposed therebetween in radially-overlapping but axially-offset relation to said trunnions, a pawl adapted to engage the rack bar and having a part-cylindrical concavity rotatably received over said bearing barrel, and securing means for retaining the pawl against detachment from said bearing barrel.

2. For use with a jack having a pedestal and a rack bar slideable in the pedestal, an improved operating handle and pawl construction comprising a handle member having spaced walls at an end portion thereof with the space between the walls opening upwardly and outwardly, a trunnion formed integral with each of said side walls and projecting laterally from the outer surface of each of said side walls with the axes of the trunnions substantially in alignment transversely of said walls, said trunnions being adapted to be journaled in the pedestal, and bearing barrels integral with said side walls and bridging the space between said side walls and

5

disposed in spaced apart relation from one another, said bearing barrels radially-overlapping and being axially-offset from the transverse line of the axes of said trunnions, pawls adapted to engage the rack bar and having part-cylindrical concavities rotatably received one over each of said bearing barrels, and securing means for retaining the pawls against detachment from their respective bearing barrels.

ARTHUR CLIFFORD HOWARD.
